UNITED STATES PATENT OFFICE.

FRED W. LEUTHESSER, OF CHICAGO, ILLINOIS, ASSIGNOR TO MONASH-YOUNKER COMPANY, OF CHICAGO, ILLINOIS, A CORPORATION OF ILLINOIS.

HOLDER FOR AIR-VALVES FOR RADIATORS.

No. 832,067.

Specification of Letters Patent.

Patented Oct. 2, 1906.

Application filed February 4, 1904. Serial No. 192,010.

To all whom it may concern:

Be it known that I, FRED W. LEUTHESSER, a citizen of the United States, residing at Chicago, in the county of Cook and State of Illinois, have invented a certain new and useful Improvement in Holders for Air-Valves for Radiators, of which the following is a specification.

This invention relates more especially to the holding or retaining of air-valves for radiators in their set position; and the invention pertains more especially to air-valves having a lateral stem or nipple entered into the wall of the radiator and furnishing communication between the radiator and the valve and having the valve set vertical in order to obtain the full benefit thereof, but is adapted for use and can be used with other species of air-valves.

It is customary to enter the valve into the wall of the radiator, so as to make a tight joint against leakage at the point of attachment of the air-valve to the radiator, and if this joint is broken or the valve turned from its set vertical position the operativeness of the valve will be impaired or destroyed. It has been found in practice that unauthorized persons, and particularly children, will turn the air-valve laterally or sidewise out of its set position, rendering it inoperative or breaking the joint between the air-valve and the radiator sufficiently to cause a leakage, and thus impair or destroy the efficiency of the valve.

The primary object of the present invention is to insure the maintaining of the air-valve in its set position and to prevent any lateral or sidewise turning of the air-valve except by an authorized person; and the invention consists in the several parts and combination of parts hereinafter described, and pointed out in the claims as new.

In the drawings, Figure 1 is an elevation of an air-valve and a portion of the wall of the radiator with the wall of the radiator in section and showing the holder or retainer of the invention in position for use; Fig. 2, a top or plan view of the holder or retainer of the invention, showing the two sections thereof united together; Fig. 3, a side elevation of the section of the holder or retainer which interlocks with the body of the air-valve; Fig. 4, a sectional elevation of the in-

terlocking section of the holder or retainer shown in Fig. 3; Fig. 5, an end elevation of the section of the holder or retainer which is to be entered into the wall of the radiator; Fig. 6, a top or plan view showing a modification in the section of the holder or retainer which interlocks with the body of the air-valve; Fig. 7, a side elevation of the interlocking section of the holder or retainer shown in Fig. 6, and Fig. 8 a sectional elevation of the interlocking section of the holder or retainer of Fig. 6.

It is not deemed necessary for the understanding of the invention to show a radiator-coil, and for this reason only a wall A of a radiator-coil is shown, it being understood that the radiator-coil can be of any usual and well-known form of construction adapted to have an air-valve applied thereto. The air-valve shown is of that type having a body B, containing any usual and well-known arrangement of devices, such as a float, for controlling the passage of air, such body, as shown, having a neck or extension b, as usual. The body or shell B of the air-valve is entered at its lower end into a base C, as usual, such base having on its bottom a wall C', with the usual conduit or passage therethrough opening into the bottom of the valve and terminating in an end or nipple c, preferably tapered and having on its exterior a screw-thread and threaded into a hole a in the wall of the radiator, so as to make a tight joint between the end or nipple and the wall of the radiator.

Air-valves for radiators are generally attached so as to stand vertical and when in place should be held in their vertical or adjusted position, and for this purpose the holder or retainer of the invention is intended. This holder or retainer consists of a section D, in the shape preferably of a band or rim, which, as shown in Figs. 2, 3, and 4, is of an oval shape and has an oval-shaped hole or opening d, which may have its walls slightly tapered upwardly, as shown in Fig. 4, and this section D of the holder or retainer on one side has a lug or ear d' for uniting the section D with its companion section. The companion section E of the holder or retainer is in the form of a solid plug, preferably tapered and having on its exterior face a screw-thread, which enables the plug to be thread-

ed into a hole a' , formed therefor in the wall of the radiator, so as to make a tight joint between the plug and the wall of the radiator against leakage. The section E has extending from the outer end of its plug portion a pair of ears or lugs e , between which is an opening or space e' , into which is entered the lug or ear d' . The two sections D and E of the holder or retainer are secured together in the construction shown by a screw F, for which purpose one or both of the ears or lugs E is provided with a screw-threaded hole for the passage of the stem of the screw, and, as shown, the lug or ear d' is provided with a hole f , through which the stem of the screw F passes, uniting the two sections of the holder or retainer one to the other.

The construction shown in Figs. 6, 7, and 8 illustrates a modification in which the wall or rim of the section D of the holder or retainer is in the shape of a circle instead of being an oval, and the hole d' in the rim or wall of the section D is circular, having cylindrical side walls, as shown in Figs. 6 and 8. The neck or lug d' instead of having a circular hole f has an elongated hole f' for the passage of the stem of the screw in uniting the two sections of the holder or retainer one to the other. It is to be understood that the shape of the sections of the holder or retainer can be varied to suit the requirements for use with air-valves of varying constructions; but it is preferred, and in all cases desirable, that the section E should have a taper, forming a plug, in order to insure a tight joint around the section at its entering-point into the wall of the radiator.

In use the air-valve is fixed in position on the radiator by entering the hollow nipple or plug c into the wall of the radiator, so as to make a tight joint. This locates the position of the air-valve and enables the workman or mechanic to properly locate the place for making the hole in the wall of the radiator for inserting the section E of the holder or retainer, and this screw-threaded hole a' can be made by the use of suitable tools. Where the holder or retainer is made in two sections, the section E can be entered into the wall of the radiator first, and the section D can be slipped over the end b or other portion of the valve and brought into position for its lug or neck d' to enter between the lugs or ears e for the holes between the several lugs to align, after which the screw F can be inserted, uniting the two sections one to the other and locating the holder or retainer in a fixed position with the air-valve caught thereby and held against lateral turning or twisting. The elongated opening d in the wall or rim of the section D allows of a slight movement endwise for adjusting purposes, so as to insure the necessary contact of the wall or rim with the entered portion of the air-valve to prevent lateral or side play, and in the construc-

tion of the section D shown in Figs. 6, 7, and 8 this endwise movement for adjusting purposes is permitted by the elongated slot or hole f' , through which the locking-screw F passes.

The holder or retainer is preferably made in two sections, as by that arrangement it can be placed in position and be made to engage with the air-valve readily and quickly, and by having adjusting means between the two sections the relation of the holder or retainer as a whole to the position of the air-valve can be regulated so as to insure a positive retention of the air-valve in its set or adjusted position and against lateral or side turning or swing.

What I regard as new, and desire to secure by Letters Patent, is—

1. In combination with a radiator having an air-valve screwed thereto, a holder or retainer for maintaining the air-valve in its set position, consisting of two sections, one of the sections being in the form of a ring encircling the valve, and the other section being in the form of a plug screw-threaded into the radiator, and a separable connection for allowing the ring-section to be engaged with and disengaged from the plug-section, substantially as described.

2. In combination with a radiator, an air-valve having a nipple screw-threaded into the radiator, a holder or retainer for maintaining the air-valve in its set position, said holder consisting of two sections, one of the sections being secured to the radiator and the other section secured to the valve, and a separable connection for the two sections, substantially as described.

3. In combination with a radiator, an air-valve having a nipple extending in transverse relation to the valve and screw-threaded into the radiator, and a holder for maintaining the valve in set position, consisting of two sections, one of the sections being in the form of a plug screw-threaded into the radiator, and the other section being in the form of a ring encircling the valve and a separable connection for the two sections, substantially as described.

4. In combination with a radiator, an air-valve consisting of an elongated shell terminating at its upper end in a cap of reduced diameter and provided at its lower end with a nipple screw-threaded into the radiator, and a holder consisting of two sections, one section being in the form of a ring encircling the valve, and the other section being in the form of a screw-threaded plug entered into the radiator, and a separable connection between the two sections, substantially as described.

5. The combination with an air-valve casing provided with a threaded attaching-nipple, of a ring fitted over the upper portion of the casing and provided with an apertured

lug, a threaded plug adapted for attachment to a radiator and provided with an apertured lug, and a fastening device passed through said apertures and securing the lugs together, the construction and arrangement of the parts being such that when the threaded nipple is screwed to a radiator and the ring and plug are in position and attached the said nipple cannot be unscrewed, substantially as described.

6. The combination with an air-valve casing provided with a threaded attaching-nipple, of a ring fitted over the upper portion of

the casing, a threaded plug adapted for attachment to the radiator, and a connection between said plug and ring, the construction and arrangement of the parts being such that when the threaded nipple is screwed to a radiator and the ring and plug are in position and attached the said nipple cannot be unscrewed, substantially as described. 15
